United States Patent Office.

G. L. MILLER, OF PONTIAC, MICHIGAN.

Letters Patent No. 77,515, dated May 5, 1868.

IMPROVEMENT IN TRACE-HOOKS.

The Schedule referred to in these Letters Patent and making part of the same.

TO ALL WHOM IT MAY CONCERN:

Be it known that I, G. L. MILLER, of Pontiac, in the county of Oakland, and State of Michigan, have invented certain new and useful Improvements in Trace-Hook, &c.; and I do hereby declare that the following is a full and complete description of the same, reference being had to the accompanying drawings, making a part of this specification, in which—

Figure 1 is a top side view of the hook, with the trace-eye attached.

Figure 2 is an under side view of the hook.

Figure 3 is an end view of the same.

Figure 4 is a view of the hook and eye.

Like letters of reference refer to like parts in the views.

This device consists of the shank A, fig. 1, which is screwed into the end of the whiffle-tree in the ordinary way. The hook B, fig. 3, is broad and flat, and curved in the peculiar manner, as represented in the drawing, in which it will be seen that one edge of the hook, at C, fig. 4, is much thicker than the relative opposite one, which is brought nearly to a thin edge, so that on introducing the hook into the eye C', the thick edge will be at the longest transverse diameter of the hole, and the thin one at the shortest, as shown in figs. 2 and 4, which shows the hook as being partially inserted in the eye; and when the hook is wholly inserted, the eye will encircle the neck D, as shown in fig. 1, and draws from the same; the hook preventing the eye from becoming unhooked, which it cannot possibly do, as the width of the base of the hook is much greater than the transverse diameter of the eye, which, to be released from the hook, must be first turned upward to a vertical direction, and thus carried back around the curve to the end of the hook.

This trace-hook is simple in its structure, and durable, as the draught, as above said, is not from hook, but on the neck; hence it is not liable to break, and cannot unhook without assistance. It is safe, and requires no spring or leather to fasten the trace-eye, and no special skill to manipulate it.

What I claim as my improvement, and desire to secure by Letters Patent, is—

The herein-described trace-hook, when constructed in the manner as set forth, as a new article of manufacture.
